UNITED STATES PATENT OFFICE.

JOHN G. BROKAW, OF SOMERVILLE, NEW JERSEY.

DESIGN FOR A SCARF-PIN.

SPECIFICATION forming part of Design No. 22,036, dated December 6, 1892.

Application filed September 2, 1892. Serial No. 444,907. Term of patent 3½ years.

To all whom it may concern:

Be it known that I, JOHN G. BROKAW, of Somerville, in the county of Somerset and State of New Jersey, have invented a new and 5 original Design for a Scarf-Pin, of which the following is a specification.

Reference is had to be to the accompanying drawing, forming a part of this specification, in which the figure is a face view showing my 10 design.

The body A of the device is an oval ring having circular and cylindrical projections on both of its longer sides. A T-shaped bar D traverses the ring on the line of its longer 15 axis and has the following ornamental append-

age, namely: a disk E, ornamented by the representation of an eye, a disk G, ornamented by the representation of a heart, and intermediately of these two is a representation F of clasped hands. On the lower end of the 20 bar D is a larger disk C. A laterally-curved bar is arranged on one side of the oval ring A.

I claim—

The design for a scarf-pin herein shown and described.

JOHN G. BROKAW.
